COWL VENTILATOR STRUCTURE

Otto F. Graebner, Detroit, Mich., assignor to The Murray Corporation of America, Detroit, Mich., a corporation of Delaware

Application October 11, 1937, Serial No. 168,406

2 Claims. (Cl. 98—2)

This invention relates to vehicle body construction and particularly relates to a cowl ventilator construction.

One of the primary objects of the present invention is to provide a cowl opening which is defined by a channel formed integrally with the cowl.

Another object of the present invention is to provide a cowl ventilator structure having a channel adjacent the cowl opening of such a construction that water collected within the channel may be effectively drained toward a drain opening in the channel.

A further object of the present invention is to provide a cowl ventilator structure having a channel adjacent the cowl opening within which a sealing strip is located of such construction as to provide a drain passage by which water collected within the channel is drained toward a drain opening formed in the cowl.

Another object of the present invention is to provide a cowl ventilator structure in which the ventilating opening may be effectively sealed and in which any moisture or water collected adjacent the ventilating opening may be effectively carried away and discharged.

Other objects of the invention will become apparent from the following specification, the drawing relating thereto, and from the claims herein-
30 after set forth.

In the drawing, the single figure is a fragmentary perspective view with parts broken away illustrating parts in cross-section of a cowl ventilator construction embodying features of the present invention.

Referring to the drawing, a cowl panel 10 is illustrated having a ventilator opening therethrough which is defined by an upwardly opening channel portion 12. The channel portion 12 is formed integrally with the cowl panel 10, preferably by drawing the portion 12 into the form of a channel after the cowl has been formed, which provides a simplified and economical manner of forming the cowl ventilating structure. The channel 12 has an outer wall portion which is of gradually increasing depth from a point indicated at 14, in both directions from the point 14 around the channel 12 to a drain opening 16. The drain opening 16 has a short tubular member 18 associated therewith which is adapted to have an elongated conduit member connected thereto which may extend to a suitable remote location for discharging any water or the like collected within the channel.

55 A sealing strip generally indicated at 20, of a

suitable resilient material such as sponge rubber, is disposed within the channel 12. The sealing strip 20 has a substantially straight upper edge portion 22 around the periphery thereof, and also has an inwardly and downwardly sloping portion 24 which forms a drain passage. The sealing strip 20 is also of gradually increasing depth from the point indicated at 14 in both directions from the point 14 towards the drain opening 16 so that any water collected within the channel is drained 10 towards the discharge opening. A recess 26 is formed in the sealing strip 20 in overlying relation to the drain opening 16 so as to permit passage of the water directly through the drain opening.

15 A closure member 30 which is complementary in shape to the shape of the cowl ventilating opening is disposed above the cowl opening and has downwardly extending peripheral edges 32 which are adapted to engage the substantially straight portion 22 of the sealing strip 20 when the closure 30 is in its closed position for sealing the cowl opening.

20 The closure 30 has suitably connected thereto on its under-surface a downwardly and rearwardly extending transverse plate member 34 to which are connected elongated rearwardly extending supporting members 36. The members 36 are pivotally mounted by pivots 38 to brackets 40 which are supported by a suitable supporting member 42, which may be a conventional part 25 of the vehicle structure. The closure member 30 is thus pivotally mounted relative to the ventilating opening, and a suitable operating arm 46 30 may be pivotally connected to the member 34 35 and extend within the passenger compartment of the vehicle for operating the closure 30 in the usual way.

35 Formal changes may be made in the specific embodiment of the invention described without departing from the spirit and substance of the invention, the scope of which is commensurate with the appended claims.

What is claimed is:

1. A cowl ventilator construction for vehicles comprising, in combination, a cowl member having a ventilating opening therethrough defined by means forming a channel, a sealing member disposed within said channel, said sealing member having a substantially straight upper edge portion and a sloping portion of gradually increasing depth around said channel to provide a sloping drain passage, and a closure member pivotally mounted for movement relative to said opening.

2. A cowl ventilator construction for vehicles,

comprising, in combination, a cowl member having a ventilating opening defined by means forming a channel of gradually increasing depth which is formed integrally with the cowl member, a sealing member disposed within said channel, said sealing member having a substantially

straight upper edge portion and a sloping portion of gradually increasing depth around said channel to provide a sloping drain passage, and a closure member pivotally mounted for movement relative to said opening.
